UNITED STATES PATENT OFFICE.

RUDOLPH HERZ, OF NEW ROCHELLE, NEW YORK, AND EUGENE CONTI, OF WEST NEW YORK, NEW JERSEY, ASSIGNEES TO ALEXANDER HERZ.

PACKAGING MACHINE.

Application filed March 25, 1918. Serial No. 224,504.

To all whom it may concern:

Be it known that we, RUDOLPH HERZ and EUGENE CONTI, citizens of the United States, and residents, respectively, of the city of New Rochelle, Westchester county, State of New York, and the town of West New York, Hudson County, State of New Jersey, the above-named petitioners, have invented an Improvement in Packaging Machines, of 10 which the following is a specification.

Our invention relates to packaging machines, and to various component parts of such machines. In one of its aspects, described herein by way of example, our invention finds 15 useful application in packaging machines which are substantially automatic in their operation. More particularly our invention may be embodied in packaging machines which are adapted not only to automatically 20 insert the articles to be packaged into containers, but also to produce such containers.

Among other objects, it is one of the objects of our invention to provide an improved construction in machines of the character described, and in the various component parts of such machines, whereby the 25 same will be rendered more certain and efficient in operation and will be otherwise improved, as will be hereinafter described.

While various articles may be packaged by means of the machines made in accordance with our invention, we have, for purposes of illustration, shown and described a type of machine more especially adapted for 35 packaging such articles as "drinking" straws or similarly shaped articles.

By way of example, we have in the accompanying drawings illustrated a preferred embodiment of our invention, and 40 therein:

Figure 1 is a plan view, somewhat diagrammatic, with certain portions omitted to render the showing clear;

Figure 2 is a diagrammatic view of the 45 article-feeding mechanism, partly in cross section;

Figure 3 is a similar view in elevation;

Figure 4 is a diagrammatic view, partly in cross section, showing the mechanism for 50 feeding a strip of paper or other material of which the container is formed;

Figure 5 is a similar view in elevation;

Figure 6 is an enlarged detail view of the mechanism for assembling or inserting the

articles into the container, this view also 55 showing the mechanism for actuating the conveyor;

Figure 7 is an enlarged cross section of said assembling or inserting means;

Figure 8 is a front elevation of said means;

Figure 9 is an enlarged detail view of the mechanism for holding the containers, in the form of tubes, on the rotary conveyor;

Figure 10 is an enlarged detail view of a portion of the feeding means, showing the 65 mechanism for holding the container open while the articles are being inserted therein;

Figure 11 is an enlarged detail view of the mechanism that actuates the article feeding device;

Figure 12 is a front elevation of the wrapper-cutting mechanism;

Figure 13 is a side elevation of the wrapper-cutting mechanism;

Figure 14 is an enlarged detail view of 75 the mechanism for holding the paper tubes or other containers in place on the rotary conveyor;

Figure 15 is a front elevation of the same, partly in cross section;

Figure 16 is a similar view showing the container about to be lowered on to the rotary conveyor;

Figure 17 is a similar view showing the container in position on the rotary conveyor;

Figures 18, 19, 20, 21, 22, 23, 24 and 25 are diagrammatic views illustrating the assembling of the straws or other articles in the containers;

Figure 26 is a detail view of a portion of 90 the straw loading mechanism;

Figure 27 is a diagrammatic view of a plurality of safety devices that may be used with our invention.

Reference will be had to the accompanying drawings forming a part of this specification, in which similar reference characters indicate corresponding parts throughout the various views.

The articles to be packaged, such as the "straws" 10 in the hopper 11 are fed on to an endless belt 12, by means of the feed wheel 13, and are then conveyed to the assembling mechanism 14 of the machine. (See Figure 2.) In wrapping the articles 10, a roll of paper or other container-forming material 15 is mounted on the frame of the machine at right angles to the straw-

feeding mechanism, and is then threaded through a set of printing rolls 16, under a guide roll 17, over an adjustable guide roll 18, under another guide roll 19, past the 5 safety device 187 and then through the crimping mechanism 20. The substantially tubular wrapper thus formed, is then cut into the desired lengths by means of a cutting mechanism 21, and the wrappers are 10 then placed on a rotary conveyor 22 which carries them into alignment with the straws 10 in the assembling mechanism 14. The straws 10 are then inserted into the wrappers in a manner hereinafter described, and 15 the finished product is then conveyed to a receptacle 23 by means of an endless belt conveyor 24.

We shall now describe in greater detail the component parts of our machine, beginning with the straw-feeding device 25. (See Figure 2.) In the hopper 11 the feed wheel 13, mounted on the shaft 26 and rotated in the direction indicated by the arrow, has a corrugated surface 27 to receive the straws 25 10 and to feed them one by one on to a belt 12. In doing this it is desirable to use a friction roll 28 which is mounted adjacent and tangent to the feed wheel 13 and rotates in the direction indicated by the arrow 30 15 thereby tending to stir up the straws 10 and facilitate the feeding of the straws into the corrugations of the feed wheel 13. The shaft 26 extends outside of the hopper 11 and has mounted thereon a ratchet wheel 35 28'', see Figure 11, which is actuated in a counter clock-wise direction by means of the pawl 29 mounted on the arm 30, which in turn is secured to the eccentric 31 upon the shaft 32, which is driven by any suitable 40 means, not shown, from the shaft 49. The pawl 29 is attached to the member 29' which is loosely mounted on the shaft 26. By means of the spring 28' the pawl 29 is kept in engagement with the teeth of the ratchet 45 wheel 28''. The arm 30 engages within the slot 30' of the member 29'. In this way the ratchet wheel 28'' and through the said wheel the shaft 26 are intermittently actuated. It will also be noted that the conveyor 50 50 12 is driven by means of the ratchet 50, which is mounted upon the shaft 51, and is actuated by the pawl 50' which is fixed to the arm 30, said shaft having fixedly mounted thereon the gear wheel 52, the teeth 55 of which mesh with the cross rods 38 of the endless conveyor 12, thereby intermittently actuating such conveyor in synchronism with the feed wheel 13 in the hopper 11. (See Figures 7 and 11.) When the straws 10 are 60 60 fed to the conveyor 12 they lie between the cross rods 38 and are fed on toward the assembling mechanism 14, where they drop by gravity into a slot 39 (see Figure 7), and under a pair of fingers 40, which, with 65 proper timing from the main drive shaft 37, oscillate in a clock-wise direction to periodically assist the straws to drop into the recess 62. This operation is brought about by means of the shaft 42 and the arm 43 having a link connection 44 with the arm 45, which is pivoted at 46, and has a turned-down member 47 riding on the cam 48 which is fixedly mounted on the shaft 49, said shaft being driven by means of the bevel gears 33, 34, 35 and 36 respectively from the main 70 75 shaft 37.

At the time the straws 10 are placed in the recess 41, there is operated a releasing mechanism for such straws. Said releasing mechanism consists of a plate 53 and a plate 54 upon which the plate 53 rests, said plates being reciprocated in opposite directions by means of the shaft 55 having a pair of links 56 and 57 mounted thereon. The shaft 55 is oscillated by means of the crank arm 58 80 riding upon cam 59 (see Figure 7), said cam being mounted upon the shaft 49 which is actuated by the bevel gears 33 and 34 from the drive shaft 37. It will be understood that when the plates 53 and 54 move in opposite directions, they separate the plates 60 and 61, carried by the plates 53 and 54 respectively, thereby allowing the straws 10 to drop into the recess 62 aided by the fingers 40, the straws now being ready to be 85 90 95 inserted into the paper tubes hereinafter to be described.

We will now describe the course of the strip of paper or other container-forming material leading up to the assembling mechanism 14 of the machine, at which point the straws or other articles are inserted into the containers. Referring to Figure 4, the roll of paper or other container-forming material 15 is threaded through the pair of printing rolls 16, under the guide roll 17 and over the adjustable guide roll 18, which is slidably mounted on a standard 63. This guide roll is adjustable in the slot 64 for the purpose of bringing the imprint on the paper into a central position on the tube after the same has been cut by means of the cutting mechanism 21. After the paper leaves the guide roll 18, it passes under the guide roll 19 and around the rod 65, (see Figure 115 1), and by any suitable means, such as the crimping mechanism shown, is formed into a continuous tubular body with the printing on the side opposite to the seam, the overlapping edges of the strip, now in tubular form, being seamed together by means of the pressure of the crimping mechanism. It will be noted that the printing of the impression on the flat strip, the subsequent rolling of the strip into tubular form, the feeding of the formed tube to the discs 68 and 69 from the forming mechanism and the flattening of the thus formed container in its received position results in the location of the printing on one flat side of the 120 125 130

container, that is to say, on the side opposite the seam. We have illustrated diagrammatically in Figure 4, a small crimping roll 66, which is pivoted in a slot in the rod 65, 5 and mounted to rotate therein. The crimping roll 66 is frictionally driven by means of a larger crimping roll 67, the rolls 66 and 67 being corrugated as shown.

After the tube thus formed leaves the 10 crimping mechanism, and has been cut into the desired lengths, such lengths are successively transferred to the rotary conveyor mechanism 22 which consists in part of a pair of corrugated discs or wheels 68 and 15 69. These corrugated wheels serve as rotary conveyors and are actuated (see Figures 6 and 8), in a clock-wise direction by means of the pawl 70 and the ratchet 71 which is mounted upon the shaft 72. The pawl 70 is 20 pivotally connected to a rocking arm 73 as at 74. The arm 73 is mounted upon the shaft 75 and leads back to a cam 76 (see Figure 1), which is mounted upon the main drive shaft 37. When the paper 15 is 25 severed as at 21, it becomes a tube 77 which is dropped by gravity on to the rotary conveyor 22 at a point corresponding to the vertical axis of the latter. This tube 77 is then carried around in a clock-wise direction 30 until it reaches a point substantially corresponding to the horizontal axis of the rotary conveyor 22. This brings the tube 77 into alignment with the straws 10 within the recess 62, which straws are to be inserted 35 into the tube 77. It will be understood that when the tube is dropped upon the conveyor 22, the end of the tube farthest away from the straws is closed, as by crimping the same by means of the end crimping rolls 78 and 40 79 respectively, which rolls are actuated by the train of gears 80 and 81. (See Figure 8.) The crimping roll 78 is fixed to the shaft which carries and is rotated by the gear 80, the latter gear being driven by the gear 81 45 which is carried and rotated by the shaft 72, the latter in its turn being driven by the pawl 70 and the ratchet 71 previously described. The crimping roll 79 on the other hand, is rotatably mounted on the swinging 50 arm 79' fixed on the shaft 79", which is carried in suitable bearings by the frame of the machine and at its outer end carries the arm 79", which is downwardly pressed by the spring 79", by which means the crimping roll 55 79 is pressed against the crimping roll 78 which, by frictional engagement with the roll 79 causes the latter to be rotated. The outer end of each tube 73 is gradually fed, by the action of the rotary conveyor discs 68 60 and 69 which carry the tube 77 in between the rotating crimping rolls 78 and 79 which act to close the end of the tube 77 by their crimping action, the rolls 78 and 79 having meshing corrugations on their outer surfaces 65 to produce the desired effect.

When the tube 77 is brought into alignment with the straws 10 in the recess 62, the rod 83 is inserted into said recess by means of the reciprocating rack 84 which meshes with the gear 85, said gear being 70 actuated by the gear 86 which in turn meshes with the rocking segmental gear 87, which is pivoted as at 88 and rocked by means of the rod 89' eccentrically pivoted to the rotated disc 89, (see Figure 5,) said disc being 75 mounted upon the shaft 90 and deriving its power from the main shaft 37 by means of the gears 91 and 92. Before the straws are inserted into the tube 77, one end of the tube 77 is slid onto the funnel or similar shaped 80 member 93, which is mounted upon an arm 94, (see Figure 4) by means of plate 100 and the tube is thus pushed towards the straws within the recess 62, said funnel member 93 serving to hold the end of the tube 77 open while the straws are being inserted. The member 93, after the straws have been 85 inserted into the tube is actuated away from the assembling mechanism by means of the reciprocating rod 94 and the cam 95 to restore the loaded tube back to its proper position on the conveyor. The rod 94 is actuated by being mounted on an arm 96, which is pivoted as at 97 to a crank 98, which in turn has a roller 99 riding on the cam 95. This cam is connected to the shaft 90 and derives its power through the gears 91 and 92 from the main shaft 37.

When the tube 77 is to be held in position on the member 93, it is, as already stated, 100 actuated towards the loading mechanism and onto member 93 by means of the backing plate 100 which is mounted upon a sliding member 101. (See Figures 8 and 9.) This sliding member 101 is actuated by means of a 105 crank member 102 which is mounted upon the shaft 103, (see Figure 9) said shaft leading back to a bell crank lever 104 which has an arm 105 riding upon the cam surface 106 mounted upon a disc which is carried by the shaft 37. When the tube 77 is actuated onto member 93, the finger member 107 (see Figures 6 and 10), which is pivotally secured to the upright member 108 at 109, 110 and is normally held against the member 93 by the compression spring 110, is raised away from the member 93 by means of a 115 rocking arm 111 which is pivoted at 112 and is rocked by means of an eccentric 113, rod 114 and the pivotal connection 115 (see Figure 10), to permit the member 93 to receive the tube 77. Further actuation of the eccentric 113 after the member 93 has been inserted within the tube 77 withdraws the arm 111 120 from the member 107 and permits the latter to be spring-pressed by the spring 110 against that end of the tube 77 which is received by member 93. By this means the tube 77 is held upon the member 93 while the member 93 receives the straws, while the 125 130

straws are being inserted into the tube, and while the member 93 is being actuated away from the straw-loading mechanism to its forward position. In the reverse operation the 5 arm 111 is actuated away from the end of the tube 77 in which the member 93 has been inserted. The member 93 is then withdrawn from this end of the tube 77, the tube 77 being prevented from following the member 93 by means of its retention under slight 10 pressure between members 178 and 179 subsequently to be described. After the straws 10 have been inserted into the tube 77, the rotary conveyor 22 moves in a clock-wise direction and carries the tube containing the straws downwardly between the crimping rolls 116 and 117, which crimp the other end of the tube 77. The crimping roll 116 is mounted on the shaft 82' which is driven 15 by the gear 82 from the gear 81. The crimping roll 117, on the other hand, is rotatably mounted on one arm of the pivoted bell crank lever 117' and is spring-pressed by the spring 117", (see Figure 10), against 20 the crimping roll 116, which by frictional engagement with the roll 117, causes the latter to be rotated. The remaining open end of each tube 77 is gradually fed by the action 25 of the rotary conveyors 68 and 69, which carry the now loaded tubes 77, between the rotating crimping rolls 116 and 117, which rolls act to close the end of the tube 77 by 30 their crimping action, the rolls 116 and 117 like the rolls 78 and 79 having meshing 35 corrugations on their outer surfaces to produce the desired result. This, it will be seen, completes the assembling of the articles within the containers and the completed package is then dropped on to the conveyor 40 belt 24.

It may here be appropriate to describe the safety devices which may be incorporated in the machine of our invention. Associated with the cross rods 38 of the conveyor 45 12 is an indicating device, preferably an electric bell, which serves to indicate when there is a defective straw between a pair of bars 38 of the conveyor 12, or when such straws are altogether missing. The indicating device may comprise a contact lever 210 pivoted as at 211 and having a portion 212 which is intended to contact with the straws between the rods 38. Preferably a plurality 50 of contacts 210 are employed, as illustrated in Figure 1. Each contact is provided with a contact portion 213 co-operating with a similar contact portion 214 connected by suitable wiring to a source of current, such as a battery 215, which is in turn connected 55 to an electric bell 216, the other terminal of the bell being preferably grounded on the machine. The arrangement is such that when a straw is missing from between a pair of rods 38, or when either end of the straw is short, in the case of defective straws,

the portion 212 of either or both contact members 210 will drop to thereby bring one or more pairs of contacts 213 and 214 together to thereby close the circuit through electric bell 216 to notify the operator that 70 a straw is missing or defective. The operator may thereupon remove the defective straw and substitute a perfect one therefor, or insert in proper position between the rods a straw where one is missing. 75

In order to prevent serious damage to the machine in case the straw-loading mechanism becomes plugged up by reason of the ejecting member 83 failing, for one reason or another, to remove the straws from the loading mechanism, we may employ safety means, preferably of the character described in Figure 27, where is shown a belt 188 which may be shifted to either the driving pulley 189 or the idle pulley 190 on the drive shaft 191. The belt is driven from either of a plurality of pulleys 192 on the main drive shaft 193. For shifting the belt from the drive pulley 189 to the pulley 190 in order to stop the machine, we prefer to employ the means illustrated, comprising a clutch 194 operable by means of a lever 195 pivoted at 196, a spring 197 being provided to normally urge the clutch so as to bring the belt into idle or non-driving position. The operation of member 195 to bring the belt into driving position serves to bring the catch 198 on member 194 into locking engagement with a core 199 of an electromagnet 200, the core being held in locking 100 engagement with catch 198 by means of a spring 201. As means for operating the electromagnetically controlled clutch we prefer to employ a source of power, as a battery 202, one terminal of which may be grounded, as at 203, and the other terminal connected both to contact 204, of the pair of contacts 204 and 205 of the safety device 187 which serves to stop the machine when the strip of container forming material is broken, and also to the insulated contact 206 of the pair of contacts 206 and 207 of safety device 208 which is for the purpose of stopping the operation of the machine 105 when the loading mechanism fails to properly function. Contacts 205 and 207 are earthed, as shown at 209 and 217 respectively. Insulated contact 206 is mounted on one part of the rod 89' made up of two telescoping, relatively movable portions 110 spring pressed together by spring 89", as more clearly shown in Figures 5 and 27. 115

It will thus be apparent that when the strip of container-forming material breaks, earthed contact 205, which is outwardly drawn by spring 218, will contact with contact 204 to thereby close one of the circuits through the electromagnet 200 to release core 199 from engagement with catch 198 120 to thereby cause belt 188 to be moved by 125 130

clutch 194 under the action of spring 197 onto idle belt 190 to thereby stop the operation of the machine. Similarly, when ejecting member 183 meets an obstacle in the straw-loading mechanism so that it cannot be properly reciprocated, such obstruction to its action will cause the two telescoping sections of rod 89 to be separated to momentarily bring contacts 206 and 207 into engagement with each other to close their circuit through electromagnet 200 to stop the operation of the machine as already described for safety device 187.

Referring now to the cutting or severing mechanism, (see Figures 12 and 13), it is desirable that while the paper in tubular form is traveling on the rod 65, the cutting mechanism, that is, the shear knives 118 and 119, should travel with the paper while the latter is being cut or severed. For this purpose the shear knives 118 and 119 are mounted to oscillate on two independent shafts, that is, the shear knife 118 is mounted to oscillate on the shaft 120 and the shear knife 119 is mounted to oscillate on the shaft 121 within which the shaft 120 is free to turn. The shaft 121 has a bevel gear 122 connected to it on its further end. This bevel gear 122 meshes with the gear 123 which in turn meshes with the gear 124, which latter gear is mounted upon the shaft 120. 126 is an arm pivoted as at 127 to the pivoted cross arm 128, which is in turn pivoted at 128' and is spring-pressed in an upward direction by the spring 127'. The arm 126, as is subsequently described, is linked as at 135 to a member 137 carrying the gear 123. This train of gears is mounted on a movable block or bearing 125 which is secured to a rack 129 which meshes with a segmental gear 130 pivoted at 131, and actuated by means of a cam 132 which is mounted upon the shaft 133, this shaft being driven through the bevel gears 35 and 36 from the main shaft 37. (See Figure 1.) When the cutting mechanism is in the act of severing the paper tube, the segmental gear 130 carries the rack 129 and the bearing block 125 in the direction in which the paper is passing until the cam 134, carried by the shaft 133, releases the arm 128, whereby said arm and the arm 126 are raised, which is linked to a member 137 at 135, said member carrying the gear 123. As the arm 126 rises, it oscillates the gear 123 and by this means the gears 122 and 124 are oscillated towards each other on the shafts 121 and 120 respectively, thereby closing the knives 118 and 119 while they are traveling in a direction with and at the same speed as the paper tube. It will be seen that when this operation is completed, the spring 138 brings the cross head carrying the knives back to its normal position as shown in Figure 12.

65 After the tube 77 has been severed from the continuous paper tube, it is necessary to keep said tube in position upon the conveyor members 68 and 69 until it reaches the assembling station at a point corresponding to the horizontal axes of the rotary conveyor, 70 and we accomplish this result by means of the mechanism shown in Figures 6, 8 and 14 to 17 inclusive. After the tube 77 has been severed, it is inserted between the plates 139 and 140 which serve to slightly 75 flatten the tube and to deliver the same in such flattened condition to the conveyor members 68 and 69. Plate 139, containing the longitudinal cavity 139', is mounted upon the standards 141 and 142, said standards carrying the slidable members 143 and 144, which are normally held in a raised position by means of the springs 145 and 146. (See Figure 16.) Secured to these slidable members 143 and 144 are the blocks 80 147 and 148, respectively, carrying the fingers 149 and 150 respectively, said fingers being pivoted to the blocks at 151 and being held in position, as shown in Figure 16, by means of the respective springs 152. Fixed 85 to the shaft 154, which is suitably supported for rotation in the frame of the machine, are the arms 153 which are actuated, (see Figure 14), by the cam 155 through the arms 156 and 157 to force the slidable members 143 and 144 downwardly against the action of the springs 145 and 146, respectively, or to permit said slidable members to be raised by such springs. The severed tube 77 is passed under the plate 139 and drops into 100 the recess as of recessed blocks 160 and 161, said blocks being in an elevated position, but not at the extreme limit of their upward movement. At this juncture the arms 153 are further raised by the action of the cam 105 155, thus permitting the slidable members 143 and 144 to be raised by the action of the respective springs 145 and 146 and the plate 140 to be passed under the tube 77, so that such tube is now held slightly flattened 110 between the plates 139 and 140. The tubes are flattened by the slight further movement of the plate 140, which is carried by the members 143 and 144 against the tube 77 within the cavity 139' of the fixed plate 139. The plate 140 is reciprocated by means of an elongated member 162, secured at one end to the member 163 which is fixed to the shaft 154 to oscillate therewith, and at the other end to the arm 164 pivotally keyed to the arm 166, the arms 164 and 166 being pivotally supported at 165. The arm 166 at its upper extremity fits within the recess 167 of the plate 140, so as to cause said plate to be reciprocated, the arm 166 being oscillated 120 through the arm 164, pivoted at 165, the link 162, the member 163 and the shaft 154, the latter being oscillated by means of the arm 157, the cam 155 and the link mechanism 156. At this point of the opera- 125 130

tion of the machine the fingers 149 and 150, pivoted at 151 to the blocks 147 and 148, each block being provided at its inner face with the pin 158, are so positioned 5 that the pins 158 will be above and free from contact with the inner face of the hubs 68' and 69' of the rotary conveyor discs or wheels 68 and 69 respectively, thus permitting the fingers 149 and 150 to be pressed 10 forward by the springs 152 and to serve in conjunction with the recessed blocks 160 and 161 respectively to position the respective ends of the tube 77, said fingers being limited in their forward motion by bearing 15 against the upper recessed faces of the respective blocks 160 and 161. When the slide- 20 members 143 and 144, carrying the blocks 147 and 148, the fingers 149 and 150, respectively, and associated mechanism, are moved downwardly by the action of the cam 155 and the associated arms 153, and the slightly flattened tube 77 enters a pair of aligned corrugations, the pins 158 are engaged by the hubs 68' and 69', respectively, 25 thereby throwing the fingers 149 and 150 back into the position shown in Figure 14, to release the ends of the tube as the latter is deposited on the corrugations, said fingers being held in this position by means of the 30 respective pawls 159, the hooked ends of which are downwardly pressed by means of the compression springs 159'. It is understood that the intermittent driving mechanism for the rotary conveyor discs 68 and 69 35 is so timed that said discs will be momentarily stationary while a tube 77 is being deposited in a pair of aligned corrugations. When the tube is to be deposited in the pair of aligned corrugations of the rotary conveyor discs 68 and 69, the plate 140 slides from underneath the tube 77, thereby leaving the tube deposited within the recesses of the blocks 160 and 161. Further downward movement of the sliding members 143 and 40 144, carrying the recessed blocks 160 and 161 respectively, causes the tube 77 to be received by a pair of aligned corrugations, (see Figure 14). At this point of the operation of the machine, the rotary conveyor discs 68 and 69 are advanced through an angle corresponding to the space of one corrugation, thus permitting the cycle of steps to be repeated. It is to be understood that while 45 the intermittent conveyor discs are stationary, not only do the aligned corrugations of such discs receive the tube 77 at a point corresponding to the vertical axes of these discs, but during such stationary period the tube which is at a point corresponding to the horizontal axes of the discs is in the act of being loaded with the straws or other articles to be packaged. In the upward or receiving movement, as contrasted with the downward or discharge movement 50 of the members 143 and 144 and the asso- ciated mechanism, the pawls 159 abut against the fixed members 168 and are tripped by such fixed members to release the fingers 149 and 150 so as to permit the next tube 77 to be properly positioned on the recessed blocks 160 and 161. To assist in guiding the tube 77 under the guide plates 176 and 177, hereinafter described, we provide the fingers 169 and 170, shown in Figures 1 and 9. These fingers are actuated by means of a 55 link 171 pivoted to an arm 172, which is mounted upon a shaft 173, said shaft having a member 174 which rides upon a cam 175 secured to the shaft 37. It will be seen, from Figure 1, that the fingers 169 and 170 are operated directly from the cam 175 by means of the action of the shaft 173. It is to be understood that the operating mechanism for the fingers 169 and 170 is so timed that the said fingers will be actuated into 60 contact with the conveyor discs 68 and 69 respectively, immediately after a newly formed tube 77 has been deposited in a pair of aligned corrugations of said discs, the said fingers making contact along those portions of the respective conveyor discs 68 and 69 which immediately precede the respective guide plates 176 and 177. After the tube 77 leaves the mechanism illustrated in Figures 6, 8 and 14 to 17 inclusive, it is held in position on the conveyor members 68 and 69 by means of the guide plates 176 and 177 shown in Figures 6 and 8, until it reaches the horizontal axis of the rotary conveyor 68 and 69, (see Figure 6), at which point the elongated recessed cross bar 178 is withdrawn from the stationary bar 179 to permit the bar 178, on the return movement of the same, to receive the tube 77 in the recess 185 to position said tube 105 during the loading operation. The bars 178 and 179 constitute supporting means for the tubular container which prevent buckling or bending thereof as the straws are inserted longitudinally into the same. The bar 178 is actuated by the cross head 180 sliding upon a sleeve 180' fixed to the shaft 72, said cross head being actuated by means of an arm 181 pivoted to an arm 182 which is mounted upon the shaft 75 which carries a 110 member 183, said member being actuated by means of a cam 184. (See Figure 1.) It will also be seen, referring to Figure 8, that the recess 185 is located in the cross piece 178 to hold the tube 77 in such a position that the member 93 will easily find the end of the tube 77. When the tube 77 has received the straws or other articles to be packaged, and reaches the bottom of the rotary conveyor members 68 and 69, it is 115 sometimes found necessary to positively release the tube 77 from the aligned corrugations of said conveyor members. For this purpose we provide an arm 186 which is mounted on the shaft 75 and works in unison 120 with the arm 181. The arm 186 is actuated by a cam 187 secured to the shaft 75. The cam 187 is so timed that when the tube 77 reaches the bottom of the rotary conveyor members 68 and 69, the arm 186 will 125 130

with the member 183, thereby operating downwardly to release the tube 77 from the aligned corrugations of the conveyor.

The operation of the machine, which is apparent from the foregoing description, may be summarized as follows: For the purpose of diagrammatically indicating the operation of the machine, we have diagrammatically illustrated in Figures 18, 19, 20, 21, 22, 10 23, 24 and 25, the various operations that the strip 15 and the straws 10 go through while the machine is in operation. Figures 18 and 19 illustrate the tube in the act of being sealed, seamed, crimped or otherwise 15 closed at one end by means of the rolls 78 and 79. Figure 20 shows the guiding member 93 positioned in the open end of the tube 77, the member 93 being also shown in Figure 22 when drawn to its position, fully 20 loaded, nearest to the conveyor. After the straws have been inserted into the tube 77, the latter is carried around the rotary conveyor to the position indicated in Figures 23 and 24. The open end of the tube is now 25 crimped or otherwise closed by means of the rolls 116 and 117. Figure 25 is a view in elevation, partly broken away, of the complete product showing the straws within the sanitary container, the tube being shown 30 closed, as by crimping, at both ends and along the longitudinal seam of the same.

It is to be understood that while the straws 10 are intermittently fed out of the container 11 on to the intermittently actuated endless conveyor 12, the speed at which 35 the straws are fed on to such conveyor is such that two straws are fed into the recess 62 of the loading mechanism while one tube is being deposited on the conveyor or being 40 loaded with the straws.

It is to be understood also that the fingers 40, best shown in Figure 7, are so operated that the said fingers will be rotated in a counter clock-wise direction into a substantially 45 vertical position clear of the opening 39 and the space 41 to permit two straws to fall into the space 41, and that when the plates 60 and 61 are separated to permit these two straws to fall into the recess 62, the fingers 50 40 are rotated in a clock-wise direction to press against said straws to assist the latter into the recess 62. The operation of the fingers 40 and of the plates 60 and 61 is so timed that the two straws are deposited in 55 the recess 62 before another straw enters the space 39, no further straws entering such space 39 until the fingers 40 are again in a vertical position and the plates 60 and 61 have moved together to cover the recess 62.

60 It is also to be understood, with reference to the operation of the cutting or severing mechanism, best shown in Figures 12 and 13, that while the shear knives 118 and 119 move in the same direction and at the 65 same speed as the continuously moving

tubular member, of which the tube 77 is to be formed, while the cutting operation is in progress, after the cut has been made the shear knives still continue to move a short distance in the same direction, but at a 70 slightly increased speed, whereby the tube 77 which has by this time been deposited in a pair of aligned corrugations of the conveyor discs 68 and 69 and is already being moved forward by the rotation of said conveyor discs, is pushed forward in its aligned corrugations by the lower shear knife 119. The increased speed of the shear knives 118 and 119 permits such knives to become 75 slightly clear of the nearer end of the next following tube 77, and thus permits said knives to be opened and the succeeding tube to pass between the same towards the conveyor mechanism. At this point the shear knives 118 and 119, now open and having 80 between them the moving hollow member which is to form the next tube 77, begin their return movement and when said return movement is completed, the cycle of operations described in connection with said 85 shear knives is repeated. It is also to be understood in connection with the funnel member 93 and the backing plate 100, that said plate is so operated as to actuate the tube 77 to be loaded towards and on to the 90 funnel member 93, which latter member after the straws have been inserted into the tube, is operated to restore the tube to its 95 original position upon the conveyor discs 68 and 69.

From the foregoing description it will be seen that, by means of the machine and the component parts thereof herein described and illustrated, we accomplish the various 100 objects of our invention.

As many changes could be made in the above construction and many different embodiments of the present invention could be devised without departing from the scope thereof, it is intended that all matter contained in the above description or shown in the accompanying drawings shall be interpreted as illustrative merely and shall not be taken in a limiting sense.

What we claim is:

1. A machine for producing containers and for packaging one or more articles within each such container, comprising a continuous source of supply of material in strip form to be made into containers; printing means associated with said strip; means for forming said strip into a continuous hollow member of substantially cylindrical form; means for severing said continuous hollow member at predetermined intervals to form a plurality of substantially cylindrical containers, each such container having both ends thereof open; means for adjusting the strip with respect to said printing means and said cutting means; means 120 125 130

- for closing one end of such container; means for inserting a predetermined number of the articles to be packaged into said container; and means for closing the open end of said container after the said articles have been inserted therein.
2. A machine for producing containers and for packaging one or more articles within each such container, comprising a continuous source of supply of material in strip form to be made into containers; printing means associated with said strip; means for forming said strip into a continuous hollow member of substantially cylindrical form, comprising a member about which said strip is fed so as to surround the said member and to give the strip a substantially cylindrical form; means for severing said continuous hollow member at predetermined intervals to form a plurality of substantially cylindrical containers, each such container having both ends thereof open; means for adjusting the strip with respect to said printing means and said cutting means; means for closing one end of such container; means for inserting a predetermined number of the articles to be packaged into said container; and means for closing the open end of said container after the said articles have been inserted therein.
3. A machine for producing containers and for packaging one or more articles within each such container, comprising a continuous source of supply of material in strip form to be made into containers; printing means associated with said strip; means for forming said strip into a continuous hollow member of substantially cylindrical form, comprising a member about which said strip is fed so as to surround the said member and to give the strip a substantially cylindrical form; means cooperating with said member to join the overlapping edges of said strip surrounding the said member; means for severing said continuous hollow member at predetermined intervals to form a plurality of substantially cylindrical containers, each such container having both ends thereof open; means for adjusting the strip with respect to said printing means and said cutting means; means for closing one end of such container; means for inserting a predetermined number of the articles to be packaged into said container; and means for closing the open end of said container after the said articles have been inserted therein.
4. A machine of the character described, comprising a receptacle containing articles to be packaged; carrying means associated with said receptacle for carrying a predetermined number of said articles; means associated with said receptacle for delivering said articles to said carrying means; receiving means associated with said carrying
- means for receiving a predetermined number of said articles and comprising a member having an open-ended cavity in one face thereof extending entirely across said member for receiving said articles; means for covering and uncovering said cavity; means for assisting said articles to be inserted into said cavity; means operating on said assisting means to cause the same to insert said articles into said cavity while the same is uncovered; means for presenting the open end of a container having the other end closed to one end of the cavity; means associated with the other end of the cavity for removing the articles from said cavity and transferring them to the container; and means for closing the open end of the container when the articles have been inserted therein.
5. A machine of the character described, comprising a receptacle containing articles to be packaged; carrying means associated with said receptacle for carrying a predetermined number of said articles; means associated with said receptacle for delivering said articles to said carrying means; receiving means associated with said carrying means for receiving the predetermined number of said articles and comprising a plate-like member having an elongated open-ended cavity in one face of said member extending entirely across the same for receiving said articles; means for covering and uncovering said cavity; means for assisting said articles to be inserted into said cavity; means operating on said assisting means to cause the same to insert said articles into said cavity while the same is uncovered; means for presenting the open end of a container having the other end closed, to one end of the cavity; means associated with the other end of the cavity for removing the articles from said cavity and transferring them to the container; and means for closing the open end of the container when the articles have been inserted therein.
6. A machine of the character described, comprising a receptacle containing articles to be packaged; carrying means associated with said receptacle for carrying a predetermined number of said articles; means associated with said receptacle for delivering said articles to said carrying means; receiving means associated with said carrying means for receiving the predetermined number of said articles and comprising a plate-like member having an elongated open-ended cavity in one face of said member extending entirely across the same for receiving said articles; a pair of cover members movably mounted to cover said cavity when said cover members are shifted towards each other and to uncover said cavity when said cover members are moved away from each other; means for moving said cover members to cover and uncover said cavity; means for assisting said

- articles to be inserted into said cavity; means operating on said assisting means to cause the same to insert said articles into said cavity while the same is uncovered; means for presenting the open end of a container having the other end closed to one end of the cavity; means associated with the other end of the cavity for removing the articles from said cavity and transferring them to the container; and means for closing the open end of the container when the articles have been inserted therein. 70
- 5 75
7. A machine of the character described, comprising a receptacle containing articles to be packaged; carrying means associated with said receptacle for carrying a predetermined number of said articles; means associated with said receptacle for delivering said articles to said carrying means; receiving means associated with said carrying means for receiving the predetermined number of said articles and comprising a plate-like member having an elongated open-ended cavity in one face of said member extending entirely across the same for receiving said articles; a pair of cover members reciprocably supported in position to overlie that face of the plate-like member having the cavity therein; oscillating members associated with said cover members to move said cover members towards one another to cover the cavity and away from each other to uncover the cavity; means for assisting said articles to be inserted into said cavity; means 80

- from each other to uncover said cavity; means for assisting said articles to be inserted into said cavity; means operating on said assisting means to cause the same to insert said articles into said cavity while the same is uncovered; means for presenting the open end of a container having the other end closed to one end of the cavity; means associated with the other end of the cavity for removing the articles from said cavity and transferring them to the container; and means for closing the open end of the container when the articles have been inserted therein.
9. A machine of the character described, comprising a receptacle containing articles to be packaged; carrying means associated with said receptacle for carrying a predetermined number of said articles; means associated with said receptacle for delivering said articles to said carrying means; receiving means associated with said carrying means for receiving the predetermined number of said articles and comprising a plate-like member having an elongated open-ended cavity in one face of said member extending entirely across the same for receiving said articles; means for covering and uncovering said cavity; means for assisting said articles to be inserted into said cavity; means operating on said assisting means to cause the same to insert said articles into said cavity while the same is uncovered; means for presenting the open end of a container having the other end closed to one end of the cavity; means associated with the other end of the cavity for removing the articles from said cavity and transferring them to the container; and means for closing the open end of the container when the articles have been inserted therein.
10. A machine of the character described, comprising a receptacle containing articles to be packaged; carrying means associated with said receptacle for carrying a predetermined number of said articles; means associated with said receptacle for delivering said articles to said carrying means; receiving means associated with said carrying means for receiving the predetermined number of said articles and comprising a plate-like member having an elongated open-ended cavity in one face of said member extending entirely across the same for receiving said articles; a pair of cover members movably mounted to cover said cavity when said cover members are shifted towards each other and to uncover said cavity when said cover members are moved away from each other; means for moving said cover members to cover and uncover said cavity; pivotally supported means for assisting said articles to be inserted into said cavity; means for oscillating said pivotally supported

- same is uncovered; revoluble means for supporting a plurality of containers, each having one end open and one end closed; means for revolving said revoluble means to cause 5 the same to successively present the open end of each container to one end of the cavity, means associated with the other end of the cavity for removing the articles from the cavity and transferring them to the container and means for closing the open end of the container after the articles have been inserted therein. 10
15. A machine of the character described, comprising a continuous source of supply of material in strip form to be made into containers; means for forming said material into a continuous hollow member of substantially cylindrical form; severing means for periodically severing said hollow member at predetermined points thereof to thereby form a plurality of substantially cylindrical containers each having both ends thereof open, said severing means comprising a reciprocable support; a pair of shear knives pivotally mounted on said support; a hollow shaft carrying one of said knives at one end thereof; a second shaft within said hollow shaft carrying the other of said knives at that end of said 20 second shaft corresponding to the first-mentioned knife; means for periodically oscillating said knives in opposite directions to oscillate said knives towards one another to sever said hollow body and away from one another when the severing operation is completed; means for moving the support and the knives mounted thereon during the cutting operation in the same direction and at the same speed that the hollow member is traveling and in the reverse direction when the cutting operation is completed; means for closing one end of each container; means for inserting a predetermined number of articles to be packaged into said container; and means for closing the open end of each container after the articles have been inserted therein. 25
30. 16. A machine of the character described, comprising a continuous source of supply of material in strip form to be made into containers; means for forming said material into a continuous hollow member of substantially cylindrical form; severing means for periodically severing said hollow member at predetermined points thereof to thereby form a plurality of substantially cylindrical containers each having both ends thereof open, said severing means comprising a reciprocable support; a pair of shear knives pivotally mounted on said support; a hollow shaft carrying one of said knives at one end thereof and a gear wheel at the other end thereof; a second shaft within said hollow shaft carrying the other of said knives at that end thereof corresponding 35 to said first-mentioned knife and a gear wheel at the other end thereof; means co-operating with said gear wheels for periodically oscillating said shafts in opposite directions to oscillate said knives towards one another to sever said hollow body and away from one another when the severing operation is completed; means for moving the support and the cutting means mounted thereon during the cutting operation in the same direction and at the same speed that the hollow member is traveling and in the reverse direction when the cutting operation is completed; means for closing one end of each container; means for inserting a predetermined number of articles to be packaged into said container; and means for closing the open end of each container after the articles have been inserted therein. 40
45. 17. A machine of the character described, comprising a source of supply of material in strip form to be made into containers; means for forming said strip into a hollow member of substantially cylindrical form; means for severing said hollow member at predetermined points of the same, thereby forming a plurality of substantially cylindrical containers, each container having each end thereof open; a movable conveyor associated with said severing means and comprising a shaft; means for rotating said shaft; a pair of disc-like members mounted on said shaft to be rotated thereby, each disc-like member being provided with a plurality of pockets in its periphery co-operating with the pockets of the other disc-like member to successively receive said open-ended containers; means associated with said conveyor for successively receiving each container from the severing means and for depositing the same within a pair of said co-operating pockets, comprising a reciprocating supporting member mounted adjacent the outer face of each disc-like member, a block attached to each of said supporting members and having a recess in its periphery; means for moving said supporting members and the attached blocks in one direction to receive each of said containers as it leaves the severing means and in the opposite direction to deposit said container in a pair of said co-operating pockets; means associated with said conveyor for closing one end of each container while leaving the other end open; means for inserting articles to be packed through the open end of each container; and means associated with said conveyor for closing said open end after said articles have been inserted therein. 50
55. 18. A machine of the character described, comprising a source of supply of material in strip form to be made into containers; means for forming said strip into a hollow member of substantially cylindrical form; 60

- means for severing said hollow member at predetermined points of the same, thereby forming a plurality of substantially cylindrical containers, each container having 5 each end thereof open; a movable conveyor associated with said severing means and comprising a shaft; means for rotating said shaft; a pair of disc-like members mounted on said shaft to be rotated thereby, each 10 disc-like member being provided with a plurality of pockets in its periphery co-operating with the pockets of the other disc-like member to successively receive said open-ended containers; means associated 15 with said conveyor for successively receiving each container from the severing means and depositing the same within a pair of said co-operating pockets, comprising a reciprocating supporting member mounted 20 adjacent the outer face of each disc-like member; a block attached to each of said supporting members and having a recess in its periphery; a fixed elongated member having a recess in one side thereof for co- 25 operating with the recess in said blocks; means for moving said supporting members and attached blocks in one direction to receive each of said containers as it reaches the severing mechanism and to press it 30 against the wall of the recess of the fixed elongated member to slightly flatten the same, and in the opposite direction to deposit said container in a pair of said co-operating pockets; means associated with said 35 conveyor for closing one end of each container while leaving the other end open; means for inserting articles to be packed through the open end of each container; and means associated with said conveyor 40 for closing said open end after said articles have been inserted therein.
19. In a machine for producing containers and for packaging articles within the same, a movable conveyor comprising a shaft; means 45 for rotating said shaft; a pair of disc-like members mounted on said shaft to be rotated thereby, each disc-like member being provided with a plurality of pockets in its periphery co-operating with the pockets of 50 the other disc-like member; means associated with said conveyor and comprising a reciprocating supporting member mounted adjacent the outer face of each disc-like member; a block attached to each of 55 said supporting members and having a recess in its periphery; a fixed elongated member having a recess in one side thereof for cooperating with the recess in said blocks; a plate-like member adjacent 60 said blocks and mounted to reciprocate therein; means for moving said supporting members and the attached blocks alternately in opposite directions; and means operating simultaneously with said 65 first-mentioned moving means for moving said plate-like member in one direction to co-operate with said fixed elongated member in flattening a container and in the opposite direction to release said container to permit the same to be deposited on the conveyor. 70
20. In a machine for producing containers and packaging articles within the same, a movable conveyor comprising a shaft; means for rotating said shaft; a pair of disc-like members mounted on said shaft to be 75 rotated thereby, each disc-like member being provided with a plurality of pockets in its periphery co-operating with the pockets of the other disc-like member; means associated with said conveyor and comprising a reciprocating supporting member mounted adjacent the outer face of each disc-like member; a block attached to each of said supporting members and having a recess in its periphery; a fixed elongated member having a recess in one side thereof for co-operating with the recess in said blocks; a plate-like member adjacent 80 said blocks and mounted to reciprocate therein; means for moving said supporting members and the attached blocks alternately in opposite directions; a finger member pivoted on each supporting member; and means operating simultaneously with said first-mentioned moving means for moving said plate-like member in one direction to co-operate with said fixed elongated member in flattening a container and in the opposite direction to release said container to permit the same to be deposited on the conveyor and for causing said finger members to overlie the ends of the container while the same is on the blocks, and for releasing such ends when the container is deposited on the conveyor. 85
21. A machine of the character described, comprising a source of supply of material in strip form to be made into containers; means for forming said strip into a hollow member of substantially cylindrical form; means for severing said hollow member at predetermined points of the same, thereby forming a plurality of substantially cylindrical containers, each container having each 90 end thereof open; a movable conveyor associated with said severing means and comprising a shaft; means for intermittently rotating said shaft; a pair of disc-like members mounted on said shaft to be intermittently rotated thereby, each disc-like member being provided with a plurality of pockets in its periphery co-operating with the pockets of the other disc-like member to successively receive said open-ended containers, said shaft and the disc-like members 95 carried thereby being momentarily stationary while receiving each container; means associated with said container for successively receiving each container from the severing means and for depositing the same 100

within a pair of said co-operating pockets; means associated with said conveyor for closing one end of each container while leaving the other end open; means for inserting articles to be packed through the open end of each container; and means associated with said conveyor for closing said open end after said articles have been inserted therein along a line parallel to the line of closure of the previously closed end.

for inserting them into the container through said hollow guide member; and means for removing the guide member when said articles have been inserted into said container. 70

22. In a machine for packaging open-ended containers, a movable conveyor for successively receiving containers and comprising a shaft; means for rotating said shaft; a pair of disc-like members mounted on said shaft to be rotated thereby, each disc-like member being provided with a plurality of pockets in its periphery co-operating with the pockets of the other disc-like member to successively receive said open-ended containers and to support the same with their ends extending a substantial distance beyond said disc-like members; means associated with said conveyor for closing 25 one end of each container while leaving the other end open and comprising a crimping roll, a second crimping roll spring-pressed against said first roll and adapted to be driven thereby; means for rotating said 30 first-mentioned roll, one end of each contained being passed by the movement of the conveyor between said crimping rolls to thereby close said end; means for inserting articles to be packed through the open end 35 of each container; further means associated with said conveyor for closing the open end of each container and comprising a crimping roll, a second crimping roll spring-pressed against said first-mentioned roll and adapted to be driven thereby; and means 40 for rotating said first-mentioned crimping roll, the open end of each container being passed by the movement of the conveyor between said crimping rolls to thereby close 45 said open end.

24. In a machine for packaging open-ended containers, a movable conveyor for successively receiving containers and comprising a shaft; means for intermittently rotating said shaft; a pair of disc-like members mounted on said shaft to be intermittently rotated thereby, each disc-like member being provided with a plurality of pockets in its periphery co-operating with the pockets of the other disc-like member to successively receive said open-ended containers from said severing means, said shaft and the disc-like members carried thereby being momentarily stationary while receiving each container from the severing means; means associated with said conveyor for closing one end of each container while leaving the other end open; means for inserting articles to be packed through the open end of each container as the same is carried by the conveyor, comprising a hollow guide member; means for inserting the end of said guide member into the open end of each container; receiving means for receiving a predetermined number of said articles; means for removing said articles from the receiving means and for inserting them into the container through said hollow guide member; and means for removing the guide member when said articles have been inserted into said container. 100

23. In a machine for packaging open-ended containers, a movable conveyor for successively receiving containers and comprising a shaft; means for rotating said shaft; carrying means mounted on said shaft to be rotated thereby and provided with a plurality of pockets for successively receiving said open-ended containers from said severing means; means associated with said conveyor for closing one end of each container while leaving the other end open; means for inserting articles to be packaged through the open end of each container as the same is carried by the conveyor, comprising a hollow guide member; means for inserting the end of said guide member into the open end of each container; receiving means for receiving a predetermined number of said articles; means for removing said articles from the receiving means and

25. In a machine for packaging open-ended containers, a movable conveyor for successively receiving containers and comprising a shaft; means for intermittently rotating said shaft; a pair of disc-like members mounted on said shaft to be intermittently rotated thereby, each disc-like member being provided with a plurality of pockets in its periphery co-operating with the pockets of the other disc-like member to successively receive said open-ended containers from said severing means, said shaft and the disc-like members carried thereby being momentarily stationary while receiving each container from the severing means and supporting the same with their ends extending a substantial distance beyond said discs; means associated with said conveyor for closing one end of each container while leaving the other end open; means for inserting articles to be packed through the open end of each container as the same is carried by the conveyor, comprising a hollow guide member; means for inserting the end of said guide member into the open end of each container; receiving means for receiving a predetermined number of said articles; means for removing said articles from the receiving means and

for inserting them into the container through said hollow guide member; and means for removing the guide member when said articles have been inserted into said container.

26. In a machine for packaging open-ended containers, a movable conveyor for successively receiving containers and comprising a shaft; means for intermittently rotating said shaft; a pair of disc-like members mounted on said shaft to be intermittently rotated thereby, each disc-like member being provided with a plurality of pockets in its periphery co-operating with the pockets of the other disc-like member to receive said open-ended containers from said severing means, said shaft and the disc-like members carried thereby being momentarily stationary while receiving each container from the severing means and supporting the same with their ends extending a substantial distance beyond such disc-like members; a guard member for each disc-like member conforming to a part of the periphery of the same to keep said containers in position within said pockets until discharged therefrom; means associated with said conveyor for closing one end of each container while leaving the other end open; means for inserting articles to be packed through the open end of each container as the same is carried by the conveyor, comprising a hollow guide member; means for inserting the end of said guide member into the open end of each container; receiving means for receiving a predetermined number of said articles; means for removing said articles from the receiving means and for inserting them into the container through said hollow guide member; and means for removing the guide member when said articles have been inserted into said container.
27. In a machine for packaging open-ended containers, a movable conveyor comprising a shaft; means for intermittently rotating said shaft; a pair of disc-like members mounted on said shaft to be intermittently rotated thereby, each disc-like member being provided with a plurality of pockets in its periphery co-operating with the pockets of the other disc-like member to successively receive open-ended containers, said shaft and the disc-like members carried thereby being momentarily stationary while receiving each container; means associated with said conveyor for successively receiving each container from the severing means and depositing the same within a pair of said co-operating pockets, comprising a reciprocating supporting member mounted adjacent the outer face of each disc-like member; a block attached to each of said supporting members and having a recess in its periphery; a fixed elongated member having a recess in one side thereof for co-operating with the recess in said blocks; means for moving said supporting members and attached blocks alternately in opposite directions; means associated with said conveyor for closing one end of each container while leaving the other end open; means for inserting articles to be packed through the open end of each container as the same is carried by the conveyor, comprising a hollow guide member; means for inserting the end of said guide member into the open end of each container; receiving means for receiving a predetermined number of said articles; means for removing said articles from the receiving means and for inserting them into the container through said hollow guide member; and means for removing the guide member when said articles have been inserted into said container.
28. In a machine for packaging open-ended containers, a movable conveyor for successively receiving containers and comprising a shaft; means for intermittently rotating said shaft; a pair of disc-like members mounted on said shaft to be intermittently rotated thereby, each disc-like member being provided with a plurality of pockets in its periphery co-operating with the pockets of the other disc-like member to successively receive said open-ended containers from said severing means, said shaft and the disc-like members carried thereby being momentarily stationary while receiving each container from the severing means and supporting the same with their ends extending a substantial distance beyond said disc; means associated with said conveyor for closing one end of each container while leaving the other end open; means for inserting articles to be packed through the open end of each container as the same is carried by the conveyor, comprising a hollow guide member; means for periodically inserting said hollow guide member into the open end of each container; receiving means for periodically receiving a predetermined number of the articles to be packaged; means for positioning the container on the hollow guide member so as to move said container on said member into position to receive said articles from the receiving means; means for removing said articles from the receiving means and for inserting them into the container through said hollow guide member; and means for removing the guide member when said articles have been inserted into said container.
29. In a machine for packaging open-ended containers, a movable conveyor for successively receiving containers and comprising a shaft; means for intermittently rotating said shaft; a pair of disc-like members mounted on said shaft to be intermittently rotated thereby, each disc-like member being provided with a plurality of pockets in its periphery.

- co-operating with the pockets of the other disc-like member to receive said open-ended containers from said severing means, said shaft and the disc-like members carried thereby being momentarily stationary while receiving each container from the severing means and supporting the same with their ends extending a substantial distance beyond such disc-like members; a guard member for each disc-like member conforming to a part of the periphery of the same to keep said containers in position within said pockets until discharged therefrom; means associated with said conveyor for closing one end of each container while leaving the other end open; means for inserting articles to be packaged through the open end of each container as the same is carried by the conveyor, comprising a hollow guide member; means for periodically inserting said hollow guide member into the open end of each container; receiving means for periodically receiving a predetermined number of the articles to be packaged; means for positioning the container on the hollow guide member so as to move said container on said member into position to receive said articles from the receiving means; means for removing said articles from the receiving means and for inserting them into the container through said hollow guide member; and means for removing the guide member when said articles have been inserted into said container. 30
31. In a machine for packaging open-ended containers, a movable conveyor comprising a shaft; means for intermittently rotating said shaft; a pair of disc-like members mounted on said shaft to be intermittently rotated thereby, each disc-like member being provided with a plurality of pockets in its periphery co-operating with the pockets of the other disc-like member to successively receive said open-ended containers from said severing means, said shaft and the disc-like members carried thereby being momentarily stationary while receiving each container from the severing means and supporting the same with their ends extending the substantial distance beyond said disc; means associated with said conveyor for disclosing one end of each container while leaving the other end open; means for inserting articles to be packaged through the open end of each container as the same is carried by the conveyor, comprising a hollow guide member; means for periodically inserting said hollow guide member into the open end of each container; receiving means for periodically receiving a predetermined number of the articles to be packaged; means for positioning the container on the hollow guide member so as to move said container on said member into position to receive said articles from the receiving means; means co-operating with the closed end of the container to help position same on the conveyor to receive the said articles; means for removing said articles from the receiving means and for inserting them into the container through said hollow guide member; and means for removing the guide member when said articles have been inserted into said container. 100
32. In a machine for packaging open-ended containers, a movable conveyor for successively receiving containers comprising a shaft; means for intermittently rotating said shaft; a pair of disc-like members mounted on said shaft to be intermittently rotated thereby, each disc-like member being provided with a plurality of pockets in its periphery co-operating with the

- pockets of the other disc-like member to receive said open-ended containers from said severing means, said shaft and the disc-like members carried thereby being momentarily stationary while receiving each container from the severing means and supporting the same with their ends extending a substantial distance beyond such disc-like members; a guard member for each disc-like member
- 10 conforming to a part of the periphery of the same to keep said containers in position within said pockets until discharged therefrom; means associated with said conveyor for closing one end of each container while
- 15 leaving the other end open; means for inserting articles to be packaged through the open end of each container as the same is carried by the conveyor, comprising a hollow guide member; means for periodically inserting said hollow guide member into the open end of each container; receiving means for periodically receiving a predetermined number of the articles to be packaged; means for positioning the container on the hollow
- 20 guide member so as to move said container on said member into position to receive said articles from the receiving means; means co-operating with the closed end of the container to help position same on the conveyor to receive the said articles; means for removing said articles from the receiving means and for inserting them into the container through said hollow guide member; and means for removing the guide member when said articles have been inserted into said container; and means associated with said conveyor for closing said open end after
- 25 said articles have been inserted therein.
- 30 34. In a machine for packaging articles; means for forming a substantially cylindrical tube from a flexible strip; means for printing on said strip before the formation of the tube; means for so flattening the tube that the printing is located on a flat side of the same; means for maintaining the tube in a flattened condition; means for feeding articles into said tube; and means for crimping the ends of the tube closed while the tube is held in a flattened condition.
- 35 35. In a machine for packaging articles; means for forming a substantially cylindrical tube from a flexible strip; means for flattening said tube; means for feeding articles into said tube; and means for crimping the ends of the tube closed along substantially parallel lines.
- 40 36. In a machine for packaging articles; means for forming a substantially cylindrical tube from a flexible strip; means for flattening said tube; means for closing one end of the tube on a line substantially parallel to the long cross sectional dimension of the tube; means for inserting articles into said tube; and means for closing the open end of the tube along a line substantially parallel to the first-mentioned line of closure.
- 45 37. In a machine for packaging articles; means for flattening a substantially cylindrical flexible tube; means for closing one end of said tube along a line substantially parallel to the long cross sectional dimension of the tube; means for inserting articles into said tube; and means for closing the open end of the tube along the line substantially parallel to the first-mentioned line of closure.
- 50 38. In a machine for packaging articles in a flexible tube having one cross sectional dimension greater than the other; means for flattening the flexible tube; means for clos-

ing one end of said tube on a line substantially parallel to the long cross sectional dimension of the tube; means for inserting articles into the tube; and means for closing the open end of the tube along a line substantially parallel to the first-mentioned line of closure.

39. In a machine for packaging articles in flexible tubes having one cross sectional dimension greater than the other; means for inserting articles into said tube; and means for closing the ends of the tube in such manner that the original cross sectional form of the tube will be maintained.

40. In a machine for packaging articles; means for forming a substantially cylindrical tube from a flexible strip; means for flattening the tube; means for crimping one end of the tube closed; means for presenting the tube to the crimping means so that the line of closure will be substantially parallel to the long cross sectional dimension of the tube; means for inserting articles into the tube; and means for crimping the other end of the tube closed, said tube presenting means being operative to present the tube to the second-mentioned crimping means so that the line of closure will be substantially parallel to the first-mentioned line of closure.

41. In a machine for packaging articles; means for forming a substantially cylindrical tube from a flexible strip; means for flattening said tube; means for closing one end of the tube; means for feeding articles into said tube; means for closing the other end of said tube; means for conveying the tube successively to the first mentioned closing means, the article inserting means and the second mentioned closing means and for maintaining said tube in its flattened condition; and means for maintaining the tube in its flattened condition during its travel from the flattening means to the conveying means.

42. In a machine for packaging articles in a flexible tube having one cross sectional dimension greater than the other; means for closing one end of said tube; means for inserting articles into said tube; means for closing the other end of said tube; and means for conveying the said tube successively to each of said afore-mentioned means in succession and for maintaining said tube in its flattened condition during said conveying operation.

43. In a machine for packaging articles; means for forming a substantially cylindrical flexible tube; means for flattening said tube; means for closing one end of said tube; means for feeding articles into said tube; means for closing the other end of said tube; means for feeding said tube to each of said closing and article feeding

means in a path transverse to the longitudinal axis of the tube; means for successively positioning the tube with respect to the first-mentioned closing means, the article feeding means and the second-mentioned closing means.

44. In a machine for packaging articles in a flexible tube; means for feeding articles into said tube, including a tubular member having one end cut diagonally with respect to its longitudinal axis; means for bringing the tube into alignment with said tubular member; and means for forcing the tube and said tubular member into telescoped relation.

45. In a machine for packaging articles in a flexible tube; means for feeding articles into said tube, including a tubular member having one end cut diagonally with respect to its longitudinal axis; means for bringing the tube into alignment with said tubular member; means for forcing the tube and said tubular member into telescoped relation; and means for closing the ends of the said tube.

46. In a machine for packaging articles in a flexible tube; means for feeding articles into said tube, including a tubular member having means thereon to position said tube with respect to said tubular member; means for forcing the tube and said tubular member into telescoped relation; and means for closing the ends of said tube.

47. In a machine for packaging articles in a flexible tube; means for closing one end of said tube; means for feeding articles into said tube; means for closing the other end of said tube; means for conveying said tube to the closing and article feeding means in a path transverse to the longitudinal axis of the tube; means for positioning the tube with respect to the first-mentioned closing means; means for moving the tube laterally with respect to its path of movement to said article feeding means; and means for moving the tube laterally with respect to its path of movement in the opposite direction to position it for the second-mentioned closing means.

48. In a machine for packaging articles in a flexible tube; means for feeding articles into said tube; means for moving said tube longitudinally to said article feeding means; and supporting means for preventing bending of the tube during its longitudinal movement.

49. In a machine for packaging articles in a flexible tube; means for feeding articles into said tube; means for moving said tube longitudinally to said article feeding means; supporting means for guiding the tube during its longitudinal movement and for preventing bending thereof; and means for rendering said supporting means inef-

fective after said article feeding means completes its operation.

50. In a machine for packaging articles; means for forming a tube of flexible material; means for re-forming the cross section of said tube; means for feeding articles into said tube; and means for closing the ends of said tube.

51. In a machine for packaging articles 10 in receptacles; means for feeding articles into the receptacles; an article supply hopper; means for conveying said articles separately to said feeding means; and means for actuating said feeding means when at 15 least two articles have been deposited therein.

52. In a machine for packaging articles in receptacles; means for feeding articles into the receptacles, which means includes a longitudinally open cavity; an article supply 20 hopper; means for conveying said articles separately to said feeding means; and means for actuating said feeding means when at least two articles have been 25 deposited therein.

53. In a machine for packaging articles in receptacles; means for feeding articles into the receptacles, which means includes a longitudinally open cavity; means for 30 closing said cavity during the operation of the feeding means; means for conveying articles separately to said feeding means; and means for actuating said feeding means when at least two articles have been deposited 35 therein.

54. In a machine for packaging articles in receptacles; means for feeding articles into the receptacles, which means includes a longitudinally open cavity; means for 40 closing said cavity during the operation of the feeding means; means for conveying articles separately to said feeding means; and means for actuating said feeding means.

45. 55. In a machine for packaging articles in receptacles; means for feeding articles into the receptacles; an article supply hopper; means for conveying articles to said feeding means; means for actuating the 50 feeding means; and means for retaining the receptacles in fixed relation to the article feeding means during the operation of the latter.

56. In a machine of the class described 60 the combination with means for printing on a strip of flexible material of means for forming said strip into a tube and clamping the meeting edges together, means for flattening the tube with the meeting edges on one side and the printed matter on the other and means for closing the ends of the tube in such manner as to maintain the flattened condition.

57. In a machine of the class described 65 the combination with means for printing on

a strip of flexible material of means for forming said material into a flattened tube with the printed matter arranged on one side of the tube and means for closing the ends of the tube in such manner as to maintain the flattened condition.

58. In a machine for packaging drinking straws, in combination, a straw hopper, a laterally open straw holder of a shape and size to hold two straws in predetermined 70 parallel relation, means including a feed wheel having straw-carrying recesses shaped to receive one straw each for transferring straws from the hopper to the holder, means for closing said holder after two straws have 75 been delivered thereto, means for feeding a continuous strip of paper forming a tube therefrom, a cutter for severing said tube into predetermined lengths, means for holding the severed length in fixed position in 80 alignment with said straw holder, and means for transferring the two straws from the holder longitudinally into the container while held in alignment with said holder.

59. In a machine for packaging drinking 90 straws, in combination, a straw hopper, a straw holder of a shape and size to hold a plurality of straws in predetermined parallel relation, means for transferring straws from the hopper to the holder, means for closing 95 said holder after a plurality of straws have been delivered thereto, means for feeding a strip of paper and forming therefrom a tube of predetermined length, means for holding the tube in fixed position in alignment with 100 said straw holder, and means for transferring the straws from the holder longitudinally into the container while held in alignment with said holder.

60. In a machine for packaging drinking 105 straws, in combination, a straw hopper, a straw holder of a shape and size to hold two straws in predetermined parallel relation, means for transferring two straws from the hopper to the holder, means for feeding a 110 continuous strip of paper and forming a tube therefrom, a cutter for severing said tube into predetermined lengths, means for holding the severed length in fixed position in alignment with said straw holder, and means for transferring the two straws from the holder longitudinally into the container 115 while held in alignment with said holder.

61. In a machine for packaging drinking straws, in combination, a straw hopper, a laterally open straw holder, means for opening and closing said straw holder, means for transferring straws from the hopper to the holder comprising a feed wheel having notches for receiving one straw each forming the bottom of said hopper, said transferring means and said opening and closing means being operable in timed relation to cause delivery of a plurality of straws to 125 said holder while open, means for feeding a 130

strip of flexible material, and for forming said strip into a tubular container, means for holding said tubular container in alignment with the straw holder, and a plunger operable longitudinally through said holder to transfer the straws from the holder into the tubular container.

62. In a machine for packaging drinking straws, in combination, a straw holder shaped to receive two straws side by side, in predetermined relation and to retain them in such relation, means for feeding straws one by one to said holder, means for closing said holder when two straws have been delivered thereto, means for feeding and folding a flexible strip to form a tube, means for conveying the formed tube into alignment with the straw holder and for holding said tube in flattened condition, and means for transferring two straws side by side from the holder into the flattened container.

63. In a machine for packaging drinking straws, in combination, a straw holder shaped to receive two straws side by side in predetermined relation and to retain them in such relation; means for feeding straws one by one to said holder; means for closing said holder when two straws have been delivered thereto; means for conveying a tubular container to, and holding it in flattened condition in, position in alignment with the straw holder; and means for transferring the straws longitudinally from the holder to the container.

64. In a machine for packaging drinking straws, in combination, a laterally open straw holder shaped to receive two straws side by side in predetermined relation and to retain them in such relation; means for feeding straws laterally to said holder; means for conveying a tubular container to, and holding it in flattened condition in, position in alignment with the straw holder; and means for transferring the straws longitudinally from the holder to the container.

65. In a machine for packaging drinking straws, in combination, a straw holder shaped to hold two straws side by side in predetermined relation; means for feeding straws one by one to said straw holder; means for feeding a strip of flexible material, forming a tube therefrom and delivering the formed tube in flattened condition to position in alignment with the straw holder to receive straws therefrom; and means for transferring two straws longitudinally from the holder to the flattened tube.

66. In a machine for packaging drinking straws, in combination, a straw holder shaped to hold two straws side by side in predetermined relation; means for feeding straws to said holder; means for conveying a tubular container to, and holding it in flattened condition in, position in alignment with said straw holder; a funnel; means for

causing a relative longitudinal movement between said funnel and container for causing said funnel to be inserted in the end of said container; and a plunger movable in the holder for transferring two straws from said holder through said funnel to said tubular container.

67. In a machine for packaging drinking straws, in combination, a straw hopper, a straw holder having a slot of a width substantially equal to the diameter of a straw, means for feeding a plurality of straws from the hopper laterally to said holder, means for closing the open side of said holder when a predetermined number of straws have been inserted therein, means for feeding a continuous flexible strip and folding said strip to form a tube, means for severing a length of said formed tube to form a tubular container, means for transferring said tubular container to filling position in alignment with said straw holder and in position to receive the straws therefrom, and a plunger operable longitudinally through said holder to transfer the straws from said holder into said tubular container.

68. In a machine for packaging drinking straws, in combination, a straw hopper; a straw holder shaped to hold two straws side by side in predetermined relation; means for conveying straws from the hopper to the holder comprising a feed wheel having straw receiving recesses to convey the straws one by one from said hopper; means for feeding a flexible strip, folding said strip to form a tube and for securing the folded edges together; a cutter adapted to sever a length of said tube to form a tubular container; a notched wheel; and means co-operating therewith to convey said tubular container laterally to filling position and to hold it in flattened position in alignment with the straw holder to receive straws therefrom; and a plunger operable through said straw holder for transferring the straws longitudinally into the container.

69. In a machine for packaging drinking straws, in combination, a straw hopper, a holder having a slot slightly wider than the diameter of a straw and of a depth slightly greater than twice the diameter of a straw, a vertical guide for conveying the straws to said holder slot, means for delivering straws through said vertical guide to said slot comprising a feed wheel having peripheral conveying recesses to receive and transfer straws one by one from said hopper, means for closing said slot when two straws have been delivered thereto, means for feeding a continuous strip of flexible material, means for folding said strip to tubular form, means for severing a length thereof to form a tubular container, a conveyor wheel having straw-receiving recesses, means for delivering said tubular container

- to a recess in said wheel in flattened condition, means for intermittently rotating said wheel to convey said container to position in alignment with said straw holder and to hold it there, a plunger operable through said slot to transfer the two straws to the tubular container, and means operable to engage said tubular container to close both ends thereof.
- 10 70. In a machine for packaging drinking straws, in combination, a straw hopper, a holder formed to receive a plurality of straws side by side in predetermined relation, a vertical guide for conveying straws to said holder, means for delivering straws through said vertical guide, said holder comprising a separator wheel having peripheral straw-receiving recesses to receive and transfer straws one by one from said holder, means for closing said holder when two straws have been delivered thereto, means for feeding a continuous strip of flexible material, means for printing on said flexible material at a predetermined point thereon, means for folding said strip to tubular form and severing a length thereof to form a tubular container, a conveyor wheel having peripheral straw-receiving recesses, means for delivering said tubular container to a recess of said wheel in flattened condition with the printing positioned on one flat side thereof, means for intermittently rotating said wheel to convey said container to straw-receiving position in alignment with said straw holder and to hold it there, a plunger operable through said straw holder to transfer two straws to the tubular container, and means operable to engage said tubular container to close both ends thereof in a manner to preserve the flattened condition.
- 15 71. In a machine for packaging drinking straws, in combination, a straw hopper, a holder shaped to receive and retain a plurality of straws in predetermined parallel relation, means for conveying straws from said hopper to said holder comprising a feed wheel having peripheral corrugations to receive and transfer straws one by one, means for closing said straw holder when a predetermined number of straws have been delivered thereto, a container support operable to substantially enclose and support against bending a flexible tubular container in position in alignment with the straw holder, and a plunger operable longitudinally through said holder to transfer said predetermined number of straws from the holder to the tubular container.
- 20 72. In a machine for packaging drinking straws, in combination, a straw hopper, a holder shaped to receive and retain a plurality of straws in predetermined parallel relation, means for conveying straws from said hopper to said holder, means for closing said straw holder when a predetermined number of straws have been delivered thereto, a container support operable to substantially enclose and support against bending a flexible tubular container in position in alignment with the straw holder, and a plunger operable longitudinally through said holder to transfer said predetermined number of straws from the holder to the tubular container.
- 25 73. In a machine for packaging drinking straws, in combination, a straw hopper, a holder shaped to receive and retain a plurality of straws in predetermined parallel relation, means for conveying straws from said hopper to said holder, a container support operable to substantially enclose and support against bending a flexible tubular container in position in alignment with the straw holder, and a plunger operable longitudinally through said holder to transfer said predetermined number of straws from the holder to the tubular container.
- 30 74. In a machine for packaging drinking straws, in combination, a straw hopper, a holder shaped to receive and retain a plurality of straws in predetermined parallel relation, means for conveying straws from said hopper to said holder comprising a feed wheel having peripheral corrugations to receive and transfer straws one by one, means for closing said straw holder when a predetermined number of straws have been delivered thereto, a container support operable to substantially enclose and support against bending a flexible tubular container in position in alignment with the straw holder, and a plunger operable longitudinally through said holder to transfer said predetermined number of straws from the holder to the tubular container.
- 35 75. In a machine for packaging drinking straws, in combination, a straw hopper, a holder shaped to receive and retain a plurality of straws in predetermined parallel relation, means for conveying straws from said hopper to said holder comprising a feed wheel having peripheral corrugations to receive and transfer straws one by one, means for closing said straw holder when a predetermined number of straws have been delivered thereto, a container support operable to substantially enclose and support against bending a flexible tubular container in position in alignment with the straw holder, and a plunger operable longitudinally through said holder to transfer said predetermined number of straws from the holder to the tubular container.
- 40 76. In a machine for packaging drinking straws, in combination, a straw hopper, a holder shaped to receive and retain a plurality of straws in predetermined parallel relation, means for conveying straws from said hopper to said holder comprising a feed wheel having peripheral corrugations to receive and transfer straws one by one, means for closing said straw holder when a predetermined number of straws have been delivered thereto, a container support operable to substantially enclose and support against bending a flexible tubular container in position in alignment with the straw holder, and a plunger operable longitudinally through said holder to transfer said predetermined number of straws from the holder to the tubular container.
- 45 77. In a machine for packaging drinking straws, in combination, a straw hopper, a holder shaped to receive and retain a plurality of straws in predetermined parallel relation, means for conveying straws from said hopper to said holder comprising a feed wheel having peripheral corrugations to receive and transfer straws one by one, means for closing said straw holder when a predetermined number of straws have been delivered thereto, a container support operable to substantially enclose and support against bending a flexible tubular container in position in alignment with the straw holder, and a plunger operable longitudinally through said holder to transfer said predetermined number of straws from the holder to the tubular container.

In testimony whereof, we have signed our names to this specification this 2nd day of March, 1918.

RUDOLPH HERZ.
EUGENE CONTI.
